UNITED STATES PATENT OFFICE.

WILLIAM N. PIERCE AND BERTRAM C. CANDEE, OF BUFFALO, NEW YORK, ASSIGNEES
TO PIERCE FUSE CORPORATION, OF BUFFALO, NEW YORK, A CORPORATION OF
NEW YORK.

FUSE.

Application filed June 10, 1920. Serial No. 387,820.

To all whom it may concern:

Be it known that we, WILLIAM N. PIERCE and BERTRAM C. CANDEE, citizens of the United States, residing at Buffalo, in the county of Erie and State of New York, have invented new and useful Improvements in Fuses, of which the following is a specification.

This invention relates to a fuse of the re-
10 fillable ferrule type and it is the object of
this invention to provide a fuse of this character which is strong and durable, easily re-
filled and not liable to be injured when the
fuse blows out.

15 In the accompanying drawings: Figure 1 is a longitudinal section of a fuse embodying our invention. Figures 2 and 3 are vertical transverse sections of the same taken on the correspondingly-numbered lines in
20 Fig. 1.

Similar characters of reference indicate corresponding parts in the several views.

10 and 11 represent the inner and outer tubular sections of insulating material forming
25 the body of the enclosing casing of the fuse, the inner section being provided in its side with an opening 12 for the introduction of the fuse link 13 into the casing. This opening may be covered and uncovered
30 by sliding the two casing sections lengthwise relatively to one another.

Within opposite ends of the inner casing section are arranged two metal bushings 14, 15 of cup-shaped form and having their
35 concave sides facing outwardly. In their inner or convex sides the bushings are provided with attaching lugs 16, 17 to which the opposite ends of the fuse link may be detachably connected either by screws 18,
40 as shown in Fig. 1, or by any other suitable means. Each of the bushings is permanently secured to the adjacent end of the inner casing section by a pin 19 passing transversely through the same and having
45 its ends riveted over the outer side of the inner casing section.

The head at the inner end of each bushing is preferably provided with one or more vent openings 20 arranged on one side of
50 the adjacent fuse attaching lug. On its outer end the bushing 15 is provided with an external annular flange 21 which projects laterally across the adjacent ends of the inner and outer casing sections. Fitting over

this flange and the respective end of the outer casing section is a metal cap 22 which may be permanently connected with this flange by brazing, or soldering and also by means of prick punches or indentations forming spurs 23 in the flange of the cap which enter recesses in the flange, as shown in Fig. 1. The head of this cap is preferably provided with one or more vent openings 25 which are arranged out of line with the openings 20 in the respective bushing and permit the escape of gases from the interior of the casing when a fuse link blows.

The other bushing 14 has its outer end projecting beyond the adjacent end of the inner and outer casing sections and provided with an external screw thread 24. This thread is engaged by an internally screw threaded disk or ring 26 which extends across the adjacent ends of the inner and outer casing sections.

27 represents a metal cap the head of which engages the outer side of the bushing 14 and the disk thereon while its flange fits over the edge of said disk and the adjacent end of the outer casing section. This cap is preferably secured to the disk by brazing and also by indentations or punch marks 28 formed in its flange and entering the edge of the disk, and similar prick punches or spurs 29 are produced in the flange of this cap which interlock with the outer casing section, as shown in Fig. 1. The head of the last mentioned cap is also provided with one or more vent openings 30 which are out of line with the vent openings 20 in the companion bushing and permit the escape of gases due to melting of a fuse link.

The flame produced when a fuse blows is prevented from reaching the exterior of the fuse by screens preferably made of gauze or woven wire in the form of cups and each engaging its head 31 with the outer side of the adjacent pin 19 while its flange 32 bears against the bore of the respective bushing.

When the fuse is in its normal working condition, the disk 26 and cap 27 which in effect are practically one piece are interlocked with the inner casing section by the screw joint between this disk and the adjacent bushing, thereby securely holding the

outer casing section in its closed position so as to cover the fuse inlet opening 12 in the inner casing section.

Upon unscrewing the disk 26 and cap 27 from the bushing 14, the outer casing section may be slid lengthwise from the inner casing section to uncover the fuse inlet in the latter and permit of removing the remnants of a burnt fuse link and replacing the same with a new one.

This fuse is very strong and capable of withstanding any rough usage as well as internal gas pressure without destroying the same and can be very easily manipulated for refilling with new fuse links when necessary.

We claim as our invention:

1. A fuse having a fuse link and a casing provided with inner and outer tubular sections of insulating material which are movable lengthwise relatively to one another, said inner section having a side opening through which the fuse link is introduced into the casing, metal cylindrical bushings arranged in opposite ends of said inner casing section and provided at their inner ends with lugs to which opposite ends of the fuse link are connected, a cap secured to one of said bushings and loosely receiving the adjacent end of the outer casing section, and a cap secured to the opposite end of the outer casing section and detachably connected with the other bushing.

2. A fuse having a fuse link and a casing provided with inner and outer tubular sections of insulating material which are movable lengthwise relatively to one another, said inner section having a side opening through which the fuse link is introduced into the casing, metal cylindrical bushings arranged in opposite ends of said inner casing section and provided at their inner ends with lugs to which opposite ends of the fuse link are connected, screens arranged in said bushings, a cap secured to one of said bushings and loosely receiving the adjacent end of the outer casing section, and a cap secured to the opposite end of the outer casing section and detachably connected with the other bushing.

3. A fuse having a fuse link and a casing provided with inner and outer tubular sections of insulating material which are movable lengthwise relatively to one another, said inner section having a side opening

through which the fuse link is introduced into the casing, metal cylindrical bushings arranged in opposite ends of said inner casing section and provided at their inner ends with lugs to which opposite ends of the fuse link are connected, pins passing transversely through said bushings and the inner casing section, and cup-shaped screens arranged in said bushings adjacent to the outer side of said pins, a cap secured to one of said bushings and loosely receiving the adjacent end of the outer casing section, and a cap secured to the opposite end of the outer casing section and detachably connected with the other bushing.

4. A fuse having a fuse link and a casing provided with inner and outer tubular sections of insulating material which are movable lengthwise relatively to one another, said inner section having a side opening through which the fuse link is introduced into the casing, metal cylindrical bushings arranged in opposite ends of said inner casing section and provided at their inner ends with lugs to which opposite ends of the fuse link are connected, an external flange arranged at the outer end of one of said bushings, a cap secured to said flange and surrounding the adjacent end of the outer casing section, and a cap permanently connected with the opposite end of the outer casing section and detachably connected with the corresponding bushing.

5. A fuse having a fuse link and a casing provided with inner and outer tubular sections of insulating material which are movable lengthwise relatively to one another, said inner section having a side opening through which the fuse link is introduced into the casing, metal cylindrical bushings arranged in opposite ends of said inner casing section and provided at their inner ends with lugs to which opposite ends of the fuse link are connected, an external flange arranged at the outer end of one of said bushings, a cap secured to said flange and surrounding the adjacent end of the outer casing section, a disk detachably connected by a screw joint with the outer end of the other bushing, and a cap permanently connected with said disk and the adjacent end of the outer casing section.

WILLIAM N. PIERCE.
BERTRAM C. CANDEE.
